SLIDER FOR FASTENERS

George Wintritz, Springdale, Conn., assignor to
Talon, Inc., a corporation of Pennsylvania

Application July 27, 1933, Serial No. 682,479

4 Claims. (Cl. 24—205)

This invention relates to slide fasteners of a well-known type and particularly to improved means for preventing unintentional opening up of the fastener in use.

So-called lock sliders of various types have been heretofore devised and used. The purpose of such sliders is to prevent slipping of the slider back along the fastener after it has been moved to the desired position. A slider without a suitable and effective locking device will slip along the fastener elements, thus causing the fastener to open up when a lateral pull occurs in the locality of the slider. It is accordingly quite essential to have a lock slider on slide fasteners which are applied to clothing and many other articles.

The object of the present invention is to provide an improved and simplified lock slider, particularly to improve the construction and operation of the friction type lock slider, and to make it adaptable to sliders of the one-piece commercial type.

In the accompanying drawing I have shown for purposes of illustration one embodiment which my invention may assume in practice.

In this drawing:

Fig. 1 is a general plan view of a fastener constructed according to my invention;
Fig. 2 is a cross-section on line 2—2 of Fig. 1;
Fig. 3 is a longitudinal section on line 3—3 of Fig. 1; and

Fig. 4 is a perspective view of the slider with the pull member detached.

The fastener illustrated comprises a pair of flexible stringers, herein fabric tapes 6, having attached thereto fastener elements 7. These fastener elements may be of any known form and will not be described in detail. The elements illustrated correspond to a well-known type now on the market and for a full understanding of the construction and operation of the fastener, reference is made to Sundback Patent 1,219,881.

The slider for interlocking and releasing the fastener elements comprises a pair of overlying parallel wings 8 integrally connected at one end by a neck 9, and having lateral flanges 10. This structure provides a Y-shaped channel on the interior of the fastener having diverging branches 11 at the rear end with the wing connection 9 between them. The pull member 12 for actuating the slider is pivotally connected on a fixed axis 13 to a lug 14 at the rear end of the slider closely adjacent the neck 9.

In order to make the portions of the top wing adjacent the lug 14 flexible, a pair of slits 15

are cut in the wing and extend from points substantially midway between the ends of the slider longitudinally along the sides of the lug 14 and neck 9 through the end of said top wing having the connection. The pull member is formed with cams 16 on one or both sides so that when the pull is pushed down against the slider in either of its extreme positions, the cams 16 will depress the flexible portions 17 and lock the slider. The locking is accomplished through the friction caused by the clamping of the flexible portion 17 against the fastener elements 7. The locking strength depends upon the clamping force which can be quite a considerable amount due to the proximity of the pull pivot axis to the integral neck connection 9. The flexible portions 17 are connected to the slider across a relatively narrow section so that they can be easily flexed and at the same time, the strength of the slider for its normal functions has not been materially decreased.

While I have shown and described in this application one embodiment which my invention may assume in practice, it will be understood that this embodiment is merely for the purposes of illustration and description and that various other forms may be devised within the scope of my invention as described in the appended claims.

What I claim as my invention is:

1. A slider for slide fasteners comprising overlying wings, and a connection at one end, said wings and connection defining a Y-shaped channel with the connection between the diverging branches of the channel, one wing having slits extending from intermediate points through the end having the connection, and a pull member pivoted to the slider adjacent the rear end and having cams thereon for flexing the slotted portions of the wing on opposite sides of the pivot to lock the slider.

2. A slider for slide fasteners comprising overlying wings, a neck integrally connecting said wings at the rear end, a pull member having a fixed pivot at the rear end of the slider adjacent said integral connection, one of said wings having slits extending longitudinally of the slider on opposite sides of said neck from points approximately midway between the ends of the slider through the end of the wing having the connection, said pull member having cams for depressing the slotted portions of the wing to lock the slider.

3. A slider for slide fasteners comprising parallel wings, a central wing connection at one end of the slider, a lug adjacent said wing connec-

tion, a pull tab pivoted to said lug, the wing adjacent said lug having the slits 15 one on each side of said lug extending through the end of the wing having said connection and providing 5 flexible side portions 17 on opposite sides of said wing connection, and cam means on said pull tab for pressing said flexible portions inwardly to lock the slider.

4. A slider for slide fasteners comprising over-
10 lying wings and a connection between the wings

at one end, said wings and connection defining a Y-shaped channel with the connection between the diverging branches of the channel, one wing having a slit extending from an intermediate point through the end of the wing having the connection; and a pull member pivoted to the slider adjacent the end having the connection and having means thereon for flexing the slotted portion of the wing to lock the slider.
